To all whom it may concern:—

Be it known that Charles Geuner, of the City of Cincinnati, County of Hamilton, and State of Ohio, have invented or produced a new and original design for a stand for shovels and tongs and do hereby declare that the scroll and leaf work represented in the annexed drawings, marked Nos. III. and IV. is a full and exact description of the same.

What I claim and desire to secure by Letters Patent, is the new design for a stand for shovels and tongs, consisting in the ornamental figures set forth in the accompanying drawings.
